UNITED STATES PATENT OFFICE.

SOREN SORENSEN, OF MILWAUKEE, WISCONSIN, ASSIGNOR TO A. J. LINDEMANN AND HOVERSON CO., OF SAME PLACE.

DESIGN FOR A STOVE.

SPECIFICATION forming part of Design No. 34,911, dated August 6, 1901.

Application filed June 14, 1901. Serial No. 64,598. Term of patent 7 years.

To all whom it may concern:

Be it known that I, SOREN SORENSEN, a citizen of the United States, residing at Milwaukee, in the county of Milwaukee and State of Wisconsin, have invented and produced a new and original Design for Stoves, of which the following is a specification, reference being had to the accompanying drawing, forming a part thereof.

As shown in the drawing, which is a perspective view of a stove, showing my new design, the leading or material features of the design consist of a dome-shaped top *a*, having a plain rounded rim *b* overhanging the top of the body, a plain cylindrical body *c*, an oval door-frame *d*, and the door *e* in the upper part of the front of the body *c*, a protuberant circular damper *f* in the lower part of the door-frame *d*, an oblong quadrangular door-frame *g*, and door *h* in the lower part of the front of the body *c*, a base-skirting *i*, curving outwardly and downwardly from the bottom of the body *c* into an approximately quadrangular form at its outer margin, and legs *j* at the corners of the skirting expanded at the top and conforming with said skirting in contour at their junction therewith. The top *a* is surmounted by an urn-shaped ornament *k* and has two zones of leaf and scroll like or-

namentation separated from each other by a 30 constricted band *l*. In the front of the lower zone is an oblong ornamental door *m*. The door-frame *d* has a broken margin of shell, scroll, and leaf like ornaments and extends on the lower side around the damper *f*, forming an ornamental and approximately semi-circular frame therefor. The door *e* has an oblong rectangular mica frame *n* and an ornamental margin outside of said frame. The door-frame *g* and the door *h* have rounded 40 upper corners and scroll and leaf like ornamentation.

On each side of the door-frame *g* are ornamental segmental foot-rails *o*. The skirting *i* and legs *j* are ornamented with scroll, 45 shell, and leaf like ornaments.

Having described my invention, what I claim as new, and desire to secure by Letters Patent, is—

The design for a stove, substantially as 50 herein shown and described.

In witness whereof I hereto affix my signature in presence of two witnesses.

SOREN SORENSEN.
